Primary Examiner—Robert A. Delehanty

(74) *Attorney, Agent, or Firm*—Pearne & Gordon LLP

(57) **CLAIM**

The ornamental design for an modular sink, as shown and described.

DESCRIPTION

FIG. 1 is an upper right perspective view of my new design for a modular sink in accordance with the present invention; FIG. 2 is a front elevational view of the modular sink of FIG. 1;

FIG. 3 is a rear elevational view of the modular sink of FIG. 1;

FIG. 4 is a left side elevational view of the modular sink of FIG. 1;

FIG. 5 is a right side elevational view of the modular sink of FIG. 1;

FIG. 6 is a top view of the modular sink of FIG. 1; and,

FIG. 7 is a bottom view of the modular sink of FIG. 1.

The unshaded area shown in FIG. 7 forms no part of the claimed design.

1 Claim, 4 Drawing Sheets
